(57) **CLAIM**

The ornamental design for a robotic arm for medical and industrial purposes, as shown and described.

DESCRIPTION

FIG. 1 is a perspective view of a robotic arm for medical and industrial purposes showing our new design;
FIG. 2 is a left view of the article of FIG. 1;
FIG. 3 is a right view of the article of FIG. 1;
FIG. 4 is a bottom view of the article of FIG. 1;
FIG. 5 is a top view of the article of FIG. 1;
FIG. 6 is a front view of the article of FIG. 1;
FIG. 7 is a rear view of the article of FIG. 1; and,
FIG. 8 is another perspective view of the article of FIG. 1. The portions of a robotic arm for medical and industrial purposes, shown in dashed lines in FIGS. 4 and 8, are for the purpose of illustrating portions of the robotic arm for medical and industrial purposes environment that forms no part of the claimed design.
